UNITED STATES PATENT OFFICE.

EDWARD L. CHOTT, OF CHICAGO, ILLINOIS.

TEETH-CLEANING INSTRUMENT.

Application filed October 13, 1923. Serial No. 668,263.

To all whom it may concern:

Be it known that I, EDWARD L. CHOTT, a citizen of the United States, and a resident of the city of Chicago, county of Cook, and 5 State of Illinois, have invented certain new and useful Improvements in Teeth-Cleaning Instruments, of which the following is a specification.

My invention relates to new and useful 10 improvements in teeth cleaning instruments, and has for its object the provision of an improved construction of this character, which is highly efficient in use and capable of economical manufacture.

15 Other objects will appear hereinafter.

The invention consists in the combinations and arrangements of parts hereinafter described and claimed.

The invention will be best understood by 20 reference to the accompanying drawings forming a part of this specification, and in which—

25 Fig. 1 is a side view of an instrument embodying the invention shown in position of use;

Fig. 2, an enlarged section taken on line 2—2 of Fig. 1;

30 Fig. 3, a similar view showing the parts in process of manufacture;

Fig. 4, a section taken on line 4—4 of Fig. 3, and

35 Fig. 5, a view similar to Fig. 2, but showing a slightly modified form of construction.

40 The form of construction illustrated in Figs. 1 to 4, inclusive, comprises a metallic head 6 having a socket 7 in one end thereof and a central bore 8 extending through the other end and into the bottom of said socket.

45 A contact piece 9 in the form of a section of rubber tubing is inserted and secured in said socket. The bore or opening in the tube section 9 is flared at its outer end 10 to increase the size and flexibility thereof. A

50 stem 11 is driven into the bore 8 to form a shank for the tool and the contact piece 9 is secured in place by swaging the walls of the socket 7 inwardly as shown at 12 in Fig. 2. In Fig. 3, the parts are shown as

55 assembled and before the swaging operation is performed. By this arrangement a simple and effective tool is provided for use by dentists in cleaning teeth. The device is capable of economical manufacture and

55 may, therefore, be supplied to dentists at such small cost that they can afford

to discard the instrument after use on one patient only. The flare 10 in the bore of tube 9 increases the flexibility of the edge of the contact piece and thus facilitates application to the tooth and under the gums of the patient. The abrasive used in cleaning teeth will accumulate in the bore of the tube 9 and automatically feed to the contact edge thus greatly facilitating the application of the abrasive.

In the modified construction illustrated in Fig. 5, the tubing 9 is secured in place by swaging a groove 13 in the walls of socket 7. Otherwise the construction is identical with that already described.

The tool is mounted for use in the ordinary flexible shaft 14, generally in use by dentists, by inserting the stem or shank 11 in the usual way.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described comprising a head having a socket at one end and a bore extending through the other end thereof and into the bottom of said socket; a contact piece inserted in said socket, the walls of said socket being compressed inwardly to compress the inserted portion of said contact piece; and a stem inserted in the bore in said head, substantially as described.

2. A device of the class described comprising a head having a socket at one end and a bore extending through the other end thereof and into the bottom of said socket; a tubular contact piece inserted in said socket, the walls of said socket being compressed inwardly to compress the inserted portion of said contact piece; and a stem inserted in the bore in said head, substantially as described.

3. A device of the class described comprising a head having a socket at one end and a bore extending through the other end thereof and into the bottom of said socket;

a tubular contact piece in the form of a section of rubber tubing inserted in said socket, the walls of said socket being compressed inwardly to compress the inserted portion 5 of the tube; a stem driven into the bore in said head, and the bore in said tube being flared at its outer end, substantially as described.

In testimony whereof I have signed my name to this specification in the presence of 10 two subscribing witnesses.

EDWARD L. CHOTT.
